SAFETY RAZOR

John W. Ashworth, New York, N. Y.

Application September 24, 1938, Serial No. 231,467

4 Claims. (Cl. 30—52)

This invention is a safety razor of the general type normally employed for the use of a single edge blade of some particular make, but constituted, according to the present invention, to permit of the use therein of any conventional double edged blade in such manner as to expose one edge at a time.

As is well known double edged blades made by different manufacturers are provided with openings in their medial portions, to cooperate with positioning devices and such openings are of different shape according to the different manufacturer.

The present invention provides for proper positioning of the double edged blade of any manufacturer in a simple and efficient manner and in such a way as to leave the entire cutting edge of the blade, as well as the ends of the blade, adjacent the cutting edge, free and unencumbered, so as to permit more efficient shaving of re-entrant portions of the face, e. g., in dimples, hollows, etc.

The present invention in its preferred practical form comprises a guard plate and a clamping plate between which two plates the blade is gripped and held in position. The blade is adapted to be transversely flexed or bent to place it under resilient pressure and it is positioned in proper cooperative relation with the guard of the guard plate by means of positioning lugs which accurately adjust the blade in a direction normal to its cutting edge. The blade is held in adjustment longitudinally of its cutting edge by means of other positioning lugs co-acting with the ends of the blade remote from the cutting edge and in this way the cutting edge, as well as the ends of the blade adjacent thereto, are left unencumbered for the purposes stated.

In a modified form of the invention, the positioning of the blade in both directions is wholly accomplished by lugs of novel shape as will be hereinafter more fully described.

Features of the invention, other than those adverted to, will be apparent from the herein-after detailed description and claims, when read in conjunction with the accompanying drawing.

The accompanying drawing illustrates different practical embodiments of the invention, but the constructions therein shown are to be understood as illustrative only, and not as defining the limits of the invention.

Figure 1 is a perspective view of a razor of the present invention showing a double edged blade in place therein and the clamping plate in open

Figure 2 is a transverse section through the head of the razor with the clamping plate closed.

Figures 3—6 inclusive are views showing the manner in which the plate is held in position.

Figure 7 is a side elevation of the positioning lug shown in Figure 6.

Figure 8 shows another modified form of the invention.

Referring first to Figures 1—5, 1 indicates the guard plate of the razor, the same being provided at its forward edge with an appropriately shaped guard 2. Pivoted at the ends of the guard are brackets 3 of the clamping plate 4 and said clamping plate is adapted to overlie the guard plate and be locked in closed position by a resilient clip 5. A handle 6 of any suitable character is secured to the under side of the guard plate.

Mounted on the guard plate and projecting upwardly therefrom are positioning lugs 7. These lugs are spaced apart and are so shaped and located that they will cooperate with the lug openings of any conventional double edged blade to fit said openings snugly in a direction transverse of the blade and thus properly position the cutting edge of the blade with respect to the guard 2. In Figure 1, the blade is shown in dot and dash lines and is indicated at 8. This blade is of the old three-opening type. It is provided with end openings 9 and a central opening 10 which is not used in the razor of this invention.

In the structures of Figures 3—5, the blades here shown have elongated medial openings 11 of different shapes, but it will be noted that the lugs 7 are so placed and are of such size that they will fit all of said openings in a way to preclude any appreciable movement of the blade in a direction normal to its cutting edge, although in every case the lugs are spaced from the opposite ends of the openings, so as to permit of longitudinal movement of the blades. This is necessary in order that the lugs will fit all openings in a way to insure proper transverse adjustment of the blade.

The longitudinal adjustment of the blade is accomplished by means of two independent and additional lugs 12 which are stamped up from or secured to the guard plate 1 near the rear edge thereof, i. e., the edge remote from the guard. These lugs are rigid, as are the lugs 7, and the spacing between them is equal to the length of the conventional blade, so that when the blade is positioned between the lugs 12, it cannot shift longitudinally of its cutting edge. Thus the blade is held against longitudinal shifting by the lugs 12 and against transverse shifting by the lugs 7.

All of these lugs extend in a direction perpendicular to the plate 1, so that the blade may simply be dropped over them and when the razor is uncovered the blade will fall out. There are no overhanging portions which will make it difficult to insert or remove the blade.

The guard plate is provided near its rear edge with upstanding posts 13 slightly elevated above the surface of the guard plate and adapted to 10 underlie the blade resting on said plate in proper engagement with the lugs, but in lieu of the two bosses 13, as shown, a single elongated boss extending between them and embodying them may be employed. Furthermore the clamping plate 15 is provided at its hinged edge with a downwardly extending flange 14 and the parts are so associated that when the clamping plate is closed, as shown in Figure 2, with the clip 5 in engagement with the guard plate to lock the clamping plate in closed position, the flange 14 will bear against the blade between the guard 2 and the boss or bosses 13 and cause said blade to be flexed downwardly and held under tension in this condition as will be clear from Figure 2. This holds the blade under tension during the shaving operation and assures a very tight grip on the blade so that it cannot possibly shift or chatter. It has the further advantage inherent in the fact that, when the clamping plate 30 is released and swung into open position, indicated in dotted lines in Figure 2, the blade will re-act as tension is released and will jump out of the razor if the razor is slightly inclined, thus rendering it unnecessary to manually lift out the 35 blade. Thus if the razor is held over a towel, sink or other convenient support and the clamping plate is opened, the blade will eject itself. This constitutes a marked convenience and obviates the necessity of reaching in and lifting out 40 the blade with attendant dangers of the user cutting himself.

It will be noted that the entire cutting edge of the razor which overlies the guard is free and unobstructed when the razor is in use and inasmuch 45 as there are no positioning lugs at the end of the cutting edge it is possible to shave to the very end of the blade. The blade can thus enter dimples, hollows, etc., to give a clean shave. This is impossible with razors wherein positioning lugs are located at the ends of the cutting edge and such 50 is the case in practically all safety razors now in use.

The razor of this invention is extremely convenient and permits of ready reversal of the blade 55 when desired so that both edges of the blade may be successively used and the blade can be used with either face up. The blade is readily inserted and more easily removed and a comfortable clean shave is insured at all times so long 60 as the blade is in proper condition.

In Figures 6 and 7 I have shown another way of positioning the blade. I do not consider this way as good as the structure of the preceding figures, but it may be employed if desired. It 65 provides for the elimination of the lugs 12 and uses in place thereof two lugs 15 which correspond to the lugs 7 but have an additional function. These lugs 15 have widened parts 16 adapted to coat with the opening in the blade to 70 position the blade transversely and from this widened part 16 of each lug extends a tapering wedge-like fin 17 terminating in a knife-like edge adapted to engage the corresponding end of the blade opening. Such an arrangement will 75 give approximate adjustment but cannot give

the same absolutely true adjustment as is accomplished in the preceding construction and cannot be used with all blades.

Figure 8 shows another form of the invention wherein the lugs 18 which correspond to the lugs 15 are somewhat larger and made diamond shape or square in form and are set so that they extend diametrically with respect to the edge of the blade. They are of such size that they will fit into the openings of any conventional blade to 10 adjust the blade in both directions with respect to the guard. They must of course be larger than the lugs 7 and the size must be accurately made to engage all openings with a fairly snug fit.

It will be noted that in Figures 1 and 2 the 15 clamping plate has side flanges at its opposite ends which are cut away, as indicated at 19, so that blades of different length may be used in such manner that the longer blades will project through the cut away portion 19 and in this manner 20 all conventional double edged blades may be used in this razor. The cutting away 19 is made possible by the fact that the blade is engaged by the flange 14 and does not rely upon the end flanges of the clamping plate for the gripping 25 action which holds the blade in place.

Having thus fully described the invention what I claim as new and desire to secure by Letters Patent is:

1. A safety razor comprising a guard plate provided along its front longitudinal edge with a guard and near its rear longitudinal edge with at least one boss, said boss and guard serving to support a double edged blade otherwise free from contact with the guard plate, positioning lugs 35 mounted on the guard plate for positioning the blade both transversely and longitudinally with respect to the guard, and a clamping plate hinged to the guard plate at the opposite ends of the guard and adapted to be pivotally moved to overlie the blade and provided with a locking member engaging the guard plate to lock the clamping plate in closed position, said clamping plate being formed along its hinged edge with a flange adapted to bear against the blade between the 45 guard and boss and transversely flex the blade between its points of support when the clamping plate is in closed position.

2. A safety razor comprising a guard plate provided along its front longitudinal edge with a guard and near its rear longitudinal edge with at least one boss, said boss and guard serving to support a double edged blade otherwise free from contact with the guard plate, positioning lugs mounted substantially medially of the guard 55 plate and adapted to project through openings in the blade to hold the blade in proper cutting relation to the guard in a direction normal to its cutting edge, additional positioning lugs adjacent the rear edge of the guard plate and 60 spaced apart to closely receive the blade between them and adjust the blade in a direction longitudinally of its cutting edge, and a clamping plate hinged to the guard plate at the opposite ends of the guard and adapted to be pivotally moved 65 to overlie the blade and provided with a locking member engaging the guard plate to lock the clamping plate in closed position, said clamping plate being formed along its hinged edge with a flange adapted to bear against the blade between the 70 guard and boss and transversely flex the blade between its points of support when the clamping plate is in closed position.

3. A safety razor comprising a guard plate provided along its front longitudinal edge with a 75

guard and near its rear longitudinal edge with at least one boss, said boss and guard serving to support a double edged blade otherwise free from contact with the guard plate, two positioning lugs mounted on the guard plate, said lugs having thickened portions adapted to extend through the blade opening in spaced relation to the ends of said opening, to snugly fit said opening and adjust the blade in a direction normal to its cutting edge, and said lugs having oppositely extending attenuated fins terminating in knife-like edges extending to and adapted for engagement with the opposite ends of the blade opening to adjust the blade longitudinally of its cutting edge, and a clamping plate hinged to the guard plate at the opposite ends of the guard and adapted to be pivotally moved to overlie the blade and provided with a locking member engaging the guard plate to lock the clamping plate in closed position, said clamping plate being formed along its hinged edge with a flange adapted to bear against the blade between the guard and boss and transversely flex the blade between its

points of support when the clamping plate is in closed position.

4. A safety razor comprising a guard plate provided along its front longitudinal edge with a guard and near its rear longitudinal edge with at least one boss, said boss and guard serving to support a double edged blade otherwise free from contact with the guard plate, two rectangular positioning lugs mounted on the guard plate and arranged diametrically with respect to the guard and of such size that they will fit snugly in two directions the blade openings of all conventional double edged blades, and a clamping plate hinged to the guard plate at the opposite ends of the guard and adapted to be pivotally moved to overlie the blade and provided with a locking member engaging the guard plate to lock the clamping plate in closed position, said clamping plate being formed along its hinged edge with a flange adapted to bear against the blade between the guard and boss and transversely flex the blade between its points of support when the clamping plate is in closed position.
